COMBINED REFLECTOR AND HOOD COVER FOR AQUARIUMS OR SIMILAR ARTICLES

George J. Gould, 791 Meacham Ave.,
Elmont, N.Y. 11003

Filed Apr. 21, 1971, Ser. No. 136,305

Term of patent 14 years

Int. Cl. D30—02

U.S. Cl. D30—12

FIG.1

FIG.2

FIG.3

FIG.4

FIG.5

FIG. 1 is a top perspective view of a combined reflector and hood cover for aquariums or similar articles showing my design;

FIG. 2 is a top plan view;

FIG. 3 is an end elevational view as seen looking from right to left, FIG. 2;

FIG. 4 is a bottom plan view; and

FIG. 5 is a side elevational view as seen looking upward at FIG. 4.

I claim:

The ornamental design for a combined reflector and hood cover for aquariums or similar articles, as shown.
